UNITED STATES PATENT OFFICE

170,883

PLATFORM FOR FIGURINES OR THE LIKE

Edward E. Mecus, Shorewood, Wis., assignor to Dexter-Mahnke Inc., Milwaukee, Wis., a corporation of Wisconsin

Application February 9, 1953, Serial No. 23,496

Term of patent 3½ years

(Cl. D33—1)

To all whom it may concern:

Be it known that I, Edward E. Mecus, a citizen of the United States and a resident of Shorewood, Wisconsin, have invented a new, original, and ornamental Design for a Platform for Figurines or the like, of which the following is a specification, reference being had to the accompanying drawing, forming a part hereof.

The figure shown in the drawing is a perspective view of a platform for figurines or the like, showing my new design.

I claim:

The ornamental design for a platform for figurines or the like, as shown.

EDWARD E. MECUS.
